UNITED STATES PATENT OFFICE.

WALTER O. WHEELER, OF WORCESTER, MASSACHUSETTS, ASSIGNOR TO UNITED SHOE MACHINERY COMPANY, OF PATERSON, NEW JERSEY, A CORPORATION OF NEW JERSEY.

FEEDING MECHANISM FOR SHOE MACHINERY.

1,008,575.

Specification of Letters Patent. Patented Nov. 14, 1911.

Original application filed August 7, 1901, Serial No. 71,182. Divided and this application filed December 17, 1908. Serial No. 487,930.

To all whom it may concern:

Be it known that I, WALTER O. WHEELER, a citizen of the United States, residing at Worcester, in the county of Worcester and 5 Commonwealth of Massachusetts, have invented certain Improvements in Feeding Mechanisms for Shoe Machinery, of which the following description, in connection with the accompanying drawings, is a specification, like reference characters on the drawings indicating like parts in the several figures.

This invention relates to lasting machines and more particularly to that class of lasting machines wherein a single pair of pincers is provided, the point of operation of which is transferred around the shoe and the pincers made to operate successively upon different portions of the margin of 10 the upper in contradistinction to that class of lasting machines provided with a plurality of pincers or other working tools operating to last different parts of the upper simultaneously.

25 The type of lasting machine to which this invention relates is known commercially as the "hand method" lasting machine.

As is known to those skilled in the art it is desirable particularly in McKay work to 30 last the toe by progressing from the center outwardly along the side and in all work to last the sides by progressing from the toe toward the heel. This is the manner in which the best operators last shoes on the 35 present hand method machine. In lasting on such a machine the shoes are fed by hand and at the same time tipped by the operator about substantially the working point as a center so as to present the insole adjacent the 40 portion of the upper being stretched substantially at right angles to the line of up-draw movement of the pincers, thereby maintaining the insole in a correct plane for properly receiving the lasting tacks.

45 With this method of operation in view, the general object of the present invention is to provide a lasting machine of the hand method type in which the point of operation of the lasting instrumentalities is automatically transferred along the shoe being 50 operated upon, the direction of such transfer being reversed when occasion requires. These results are attained in the preferred embodiment of the invention by mounting

the shoe on a suitable jack constructed and 55 arranged to permit of vertical bodily movement and also of angular movement in such direction as to provide for a presentation of the side and end portions of the upper to the lasting instrumentalities. With this movable jack is combined an automatically operating step by step shoe feeding mechanism, the direction of feed being under the control of the operator and regulated manually according to the relative position of the shoe 60 and lasting instrumentalities. The proper angular relation between the insole and the lasting instrumentalities at the working point is obtained by manually tilting the 65 jack.

70 The invention, accordingly, contemplates the provision in a lasting machine having the usual lasting instrumentalities of an angularly adjustable jack for supporting the shoe and a co-operating automatic shoe feeding device whose direction of feed may be 75 reversed.

While it is, in some embodiments of my invention, convenient to support the shoe being lasted upon a jack, such supporting 80 means are not an essential feature of the invention since the shoe has only to be brought into the proper relation with the feeding means for the feed to take place and any convenient method of bringing about this 85 relation will suffice. For example, the shoe may be manually held in the proper relation with the feed mechanism.

Broadly stated, then, the invention comprises the provision, in a machine for use 90 in the manufacture of boots and shoes having an operating tool, or tools, of an automatic work feeding device constructed to feed the work at one time in one direction and at another time in the reverse direction, 95 the general arrangement of the machine being such that the work to be operated upon may readily be presented to and moved by the automatic feeding mechanism.

In the drawings which illustrate the feeding mechanism disclosed in Patent No. 910,251, granted to Walter O. Wheeler, January 19, 1909, of which the present application is a division, Figur 1 is an elevation showing one side of the machine; Fig. 2 is 105 an elevation showing the lower portion of the machine; Fig. 3 is a perspective view showing the feeding mechanism and operating con-

nctions therefor; Fig. 4 is an elevation of a section on line 4 of Fig. 3.

The machine comprises a column 2 whereon is supported a head 3. In the head 3 is a shaft 4 which carries a disk 5 and supports a disk 6 fast to the driving pulley which together rotate loosely on shaft 4 and are movable thereon toward and from disk 5. Disks 5 and 6 are provided with friction 10 appliances whereby, when the two are brought together, motion is imparted for revolving the shaft 4. Between the incline 7 on the head 3 and the disk 6 is a wedge 8 having connection with the treadle member 15 9 by which the wedge may be moved to force the disk members into contact for starting the machine. Said starting movement is made to take place against the tension of spring 10 which acts to withdraw the 20 wedge for stopping the machine whenever pressure is removed from the treadle. This movement also operates to apply a brake 11 on the disk 5 for promptly stopping the machine.

25 The shaft 4 extends through the head 3 and actuates, through suitable means, the various driven devices and mechanisms of the machine which briefly stated consist of the pincers 26, the presser or wiper 200, the 30 pounder 70, the slitting knife 80, the fastening supply device 59 and the means for cutting off and driving the fastenings.

In the hanger 12 depending from the head 3 is a member 13 which is supported at the 35 proper altitude for the shoe, when rested with the bottom pressed upwardly against the under side of member 13, to be in position for the pincers to go forward and grip the upper. Preferably this member has its 40 face corrugated to better engage with and prevent the shoe from slipping. This member is connected with mechanism hereinafter to be described whereby it is made to revolve at times for feeding the shoe about and 45 presenting different parts of the upper to the pincer action. For purposes of convenience this member is hereinafter referred to as a feed rest.

The machine also comprises an edge rest 50 14 arranged in position for the shoe when held upwardly against the member 13 to be pressed laterally toward the outer end face of the member 14, in which position said member 14 will bear on the upper at about 55 the point where it folds over the edge of the innersole.

In the machine represented the shoe is supported by placing the last upon a jack 19 and is presented bottom upwardly to the 60 feeding rest 13 its edge resting on the edge rest 14. To this end the jack 19 has its bottom end in ball and socket connection with the upper end of rod 21 and permits universally free rotative rocking movements. The 65 rod 21 has its bottom end connected with

treadle 22 and between the collar 23 on the rod and a bracket 24 on column 2 is a spiral spring 25 normally under tension for lifting the jack and holding it upwardly in position for pressing the shoe against the feeding rest 13 and edge rest 14 in position for the upper to be engaged by the pincers 26. The treadle may be operated for depressing the jack into position for taking off and putting on a shoe or to move the shoe out of range of the pincers. The pincers are designated by reference character 26 and are mounted on carriage 30 so as to move forwardly to the point for gripping the upper and then backwardly for pulling the upper 70 over the innersole. When lasting certain portions of the shoe the backward motion of the pincers is accompanied by a turning motion thereof. Further specific description of the pincers and the mechanism for 80 operating them will be omitted from this application since these elements are features of the applicant's Patent No. 910,251 wherein they are fully described and claimed.

Besides the mechanism already referred 90 to, this machine comprises a pounder 70, the function whereof is to pound the wrinkles from parts of the folded upper. This member is suitably mounted and reciprocated vertically upon the bottom of the 95 shoe being lasted by a suitable cam or eccentric mounted on the shaft 4 but not shown in the drawings.

In the machine represented provision is also made for slitting the edge of the upper 100 at times during the lasting process. To this end there is shown in Fig. 1 a cutter 80 and suitable connecting mechanism between the cutter and the knee lever 113 so arranged that a movement of the knee lever to one 105 side of its middle position puts into operation the cutter set for cutting the material on one side of the pincers. A counter movement of the knee lever 113 to the opposite side of its middle position will put into operation a corresponding cutter for slitting the upper on the other side of the pincers. With the knee lever in the middle position 110 there will be no movement of the cutter.

After a section of the upper material is 115 suitably strained and laid over the innersole it must be fastened in place. This is commonly done by inserting some suitable fastening device through the turned over upper into the innersole. In the present instance, the pounder 70 is employed for supporting the fastening device in position at the driven point. There is also suitable mechanism 59 for supplying fastening devices to the pounder 70 and suitable means within the 120 pounder for driving each fastening device.

The pounder, slitting knife and fastener supplying and driving mechanism will not be more particularly described herein since they constitute features of the patent before 130

referred to and of other Letters Patent No. 959,666, granted on my application wherein they have been fully described and claimed.

The lasting operation as a whole is performed step by step, different parts of the upper being presented successively to the action of the pincers. In this connection mechanism is provided whereby the shoe is automatically fed with respect to the lasting instrumentalities. To this end the feed rest 3 is constructed to be engaged by the bottom of the shoe to be lasted, and by intermittently rotating while in engagement with the same to feed the shoe step by step to the lasting instrumentalities. Rotation is imparted to the feed rest by the following mechanism:—The lever 54 (see Fig. 3) is pivoted intermediate its length and the upper end hereof engages with a suitably shaped cam 55 on shaft 4 while the lower end is pivotally and slidingly connected with the arm 50 which is mounted loosely on the feed rest. As before stated the feed rest is mounted in the hanger 12, the portion thereof which engages and feeds the work being corrugated and the outer end provided with a ratchet or toothed wheel 130. The bifurcated pawl 51 is pivoted on the arm 50 in a position to actuate the toothed wheel 130 in either direction desired as the arm 50 and pawl are oscillated by the lever 54. Motion of the feed rest in one direction is effected by the pawl arm 53. To reverse the direction of feed the pawl is moved till the other pawl arm 52 co-operates with the toothed wheel 130 and the pawl may be set in a central position out of engagement with the feeding rest whenever no automatic feeding is desired. For holding the pawl in any one of these adjusted positions it is provided with a spring pressed plunger adapted to engage notched surface of the arm 50, as shown in Fig. 4.

In lasting machines of the class represented it is common for the workman while lasting the heel to depress the last away from the pincers during the closing together of the pincer jaws, whereby gripping of the upper is avoided and to return it upwardly in position for receiving the action of the other lasting instrumentalities in order that the upper may be laid over upon the innersole and secured thereto without being subjected to the action of the pincers. In the present machine provision is made for causing said intermittent depressing movements of the shoe to take place automatically, the automatic mechanism being rendered operative by the workman when the lasting operation has progressed to the suitable portion of the shoe. To this end the lever 103 connects pivotally with the top end of rod 104, the bottom end of which connects with the treadle 22. Lever 103 is pivotally connected by its other end with the bottom end of rod

105 which extends upwardly to a cam 106 on shaft 4 against which it is yieldingly pressed by the spring 107. It will be observed that during each revolution of shaft 4 the cam 106 is moved to effect a downward movement of rod 105 which movement being transmitted to lever 103 will pass on to rod 104 and thence through the treadle to the jack rod 21. The lever 103 is provided with a shiftable fulcrum block 102, the arrangement being such that when the fulcrum block is in the position shown in Fig. 1 little or no motion is transmitted to the rod 104 while the block may be shifted by suitable means (not illustrated) toward the right 80 whereby the proper amount of motion may be transmitted to the jack for depressing the shoe.

In using the machine the jack is depressed by the foot lever 22 and the shoe 85 to be lasted is applied thereto in the usual manner, the jack being pressed upwardly by the spring 25 to present the shoe against the feed rest 13. The operator holds the part of the shoe at which the lasting is to begin, usually a point near the toe, against the edge rest 14 and after observing that the edge of the upper is located between the open jaws of the pincers, starts the machine by operating the treadle 9 connected with 90 the clutch. The pincers are first closed upon the edge of the upper, then tilted and finally carried upwardly and outwardly away from the edge of the last and over the innersole. When the upper has been drawn into position to be secured the pounding device 70 descends for hammering the upper adjacent to the place where the fastening is to be inserted. Immediately thereafter the fastening device is placed and driven through the 100 upper into the innersole after which the several parts resume their first position for repeating the operations on another portion of the upper. During the return of the pincers to position for again gripping the upper the feeding rest is actuated for advancing the shoe, this being effected by the cam 55 acting through the working lever 54, as shown in Fig. 3, to swing the pawl 51 and turn the rest. After the lasting 110 operation has proceeded along the edge of the shoe to the desired point the operator depresses the jack by means of the treadle 22 thus disengaging the shoe bottom from the feeding rest. The shoe may be now 120 manually moved to bring another portion of the edge thereof to the operating point of the lasting instrumentalities whereat the lasting operation again progresses, the rotation of the feeding rest being in the appropriate direction.

In lasting a shoe according to one preferred method of procedure the operator begins lasting at a point near the toe and lasts along that side toward the heel, the 125

operation is then interrupted and again taken up at a point near the toe but on the opposite side of the shoe. From this point the lasting progresses again toward the heel

- 5 where it is again interrupted. The remaining portion of the toe is finally lasted in two operations beginning in each case at the center of the toe and progressing first on one side and then on the other side of
 10 the toe to the point where the two previous operations began.

Having fully described my invention embodied in the best form known to me, I claim as new and desire to secure by Letters Patent of the United States:

1. In a machine for lasting shoes, the combination with means for working an upper over a last, a shoe bottom rest, and actuating mechanism for moving it whereby
 20 the shoe may be fed, of means under control of the workman for rendering said actuating mechanism operative or inoperative.

2. A lasting machine having, in combination, a shoe feeding means, and actuating mechanism for moving it in either direction whereby the shoe may be moved at one time in one direction and at another time in the reverse direction, and means for rendering said actuating mechanism operative for
 25 moving the feeding mechanism in the desired direction or inoperative to allow the feeding mechanism to remain at rest.

3. In a lasting machine, the combination with means for supporting the shoe in inverted position, shoe feeding mechanism for engaging the shoe bottom, and means to actuate said mechanism to feed the shoe in either direction, of means under the control of the operator for adjusting said actuating
 40 means to cause the shoe to be fed in the desired direction.

4. In a lasting machine, the combination with a shoe feeding member constructed and arranged to feed the shoe bottom during
 45 the lasting operation, of actuating mechanism therefor comprising a ratchet connected to the feeding member, a lever, means for oscillating the lever, and a pawl arranged to be operated by the lever and adjustable
 50 to cause the ratchet to be moved thereby in either direction.

5. In a lasting machine, the combination with a shoe feeding member, of actuating mechanism therefor comprising a ratchet
 55 connected to said feeding mechanism, a lever, means for oscillating the lever, a pawl arranged to be operated by the lever, and means by which the pawl may be adjusted into operative or inoperative relation to the ratchet.

6. A lasting machine, having, in combination, lasting instrumentalities, provision for imparting a relative movement to the lasting instrumentalities and a shoe to
 60 transfer the point of operation of said in-

strumentalities along the margin of the shoe upper, and means for changing the relative direction of said movement, substantially as described.

7. A lasting machine, having, in combination, a lasting head provided with automatically operating pincers, provision for imparting a relative movement to the pincers and a shoe to transfer the point of operation of said pincers around the shoe, and means for changing the relative direction of said movement while the pincers continue in operation, substantially as described.

8. A lasting machine, having, in combination, lasting instrumentalities, and means to transfer the point of operation of said lasting instrumentalities along the sides of the forepart of a shoe and in a direction toward the heel on each side, substantially as described.

9. A lasting machine, having, in combination, lasting instrumentalities, a feeding mechanism for imparting a relative movement to the lasting instrumentalities and a shoe, actuating means for said mechanism adapted to impart a relative movement to said parts in one direction for a time, and manually operated means for causing said actuating means to thereafter impart a relative movement to said parts in another direction for a time, substantially as described.

10. A lasting machine, having, in combination, a lasting head provided with automatically operating pincers, mechanism operating to impart a relative movement to said pincers and a shoe to transfer the point of operation of said pincers along the margin of the shoe upper, and means operatively connected to said mechanism for reversing the direction of said relative movement, substantially as described.

11. A lasting machine, having, in combination, lasting instrumentalities, a shoe feeding mechanism adapted to feed a shoe in one direction, and a controlling device operatively connected with said shoe feeding mechanism constructed and arranged to reverse the direction of feed of the shoe, substantially as described.

12. A lasting machine, having, in combination, lasting instrumentalities, a shoe feeding mechanism constructed and arranged to feed a shoe past the lasting instrumentalities in either of two directions, and means for predetermining the direction in which the shoe is to be fed, substantially as described.

13. A lasting machine, having, in combination, a lasting head provided with automatically operating pincers, means for feeding a shoe past said pincers, and means to change the direction of the feeding movement during the lasting operation substantially as described.

14. A lasting machine, having, in combination, a lasting head provided with auto-

atically operating pincers, a work feeding mechanism adapted to impart a step-by-step feeding movement to a shoe past the pincers, and provision for causing said feeding mechanism to feed the work in either of two directions, substantially as described.

15. A lasting machine, having, in combination, a lasting head provided with automatically operating pincers, means for supporting a shoe in position for the pincers to operate upon the opposite sides of the fore part of the shoe successively, and means for feeding the shoe past the pincers in opposite directions during the lasting operation on each side of the shoe, substantially as described.

16. A lasting machine, having, in combination, lasting instrumentalities, means for supporting a shoe in position for said lasting instrumentalities to initially operate on substantially the center of the toe of the shoe, and means to transfer the point of operation of said instrumentalities first to one side of the initial operative position for a time and then to the other side of said position without passing around the heel of the shoe, substantially as described.

17. A lasting machine, having, in combination, lasting pincers, a shoe support mounted to permit a presentation of different portions of the margin of the fore part of the shoe in a pre-selected sequence, a work feeding mechanism, and provision for controlling the direction of feed of said mechanism whereby all of said portions of the shoe are lasted by a transference of the working point in a direction from the toe toward the heel, substantially as described.

18. A shoe feeding mechanism for lasting

machines comprising means for engaging the bottom of an inverted shoe and actuating mechanism for causing the first mentioned engaging means to feed the shoe in either direction at the will of the operator.

19. A lasting machine having, in combination, a feeding member constructed and arranged to engage the shoe stock and means to move it in opposite directions, the combination operating for feeding the shoe, at one time in one direction and at another time in a reverse direction, the direction of the feed being under the control of the operator.

20. In a lasting machine, the combination of pincers adapted for gripping the upper and means comprising a rest for gagging the shoe in position to receive the action of the pincers, combined with means for moving the rest in opposite directions, the rest operating to feed the shoe, at one time in one direction and at another time in the reverse direction, substantially as described.

21. A lasting machine having a revolvable shoe feeding member constructed and arranged to engage the shoe stock, and means to revolve it in opposite directions, combined with means, controllable by the workman, for shifting the direction of the revolving movement of said feed member as desired during the lasting process, substantially as described.

In testimony whereof I have signed my name to this specification in the presence of two subscribing witnesses.

WALTER O. WHEELER.
